TUBE END-FLARING MECHANISM

John K. M. Harrison, Ogontz, Pa.

Application August 9, 1938, Serial No. 223,797

4 Claims. (Cl. 93—36.5)

This invention relates to tube end-flaring mechanism generally and, more particularly, aims to provide a novel means for "cold" flaring the ends of pre-formed container body shells to facilitate the application and sealing fixture therein of suitable end closures.

Other objects and ancillary advantages of the invention will appear from the following descriptive matter considered in conjunction with the accompanying drawings; while it is to be understood that the concluding claims are to be accorded a range of equivalents consistent with the state of the prior art.

In a typical embodiment of the invention, preferably adapted for operation upon suitably lined or unlined paper, fiber or analogous, container body shells use is made of a driven multiple-roller device of tapering configuration which is appropriately moved into rotative coaction with the respective open ends of the body shell to impart a slight flare to said ends.

In the drawings:

Fig. I is a view in elevation of one practical embodiment of the invention as adapted for the end-flaring of spirally-wound paper container body shells.

Fig. II is a view, partly in section, and partly in elevation, of the improved tube flaring head apart from its operating means and drawn to a larger scale than the preceding illustration; and,

Fig. III is a section on the plane III—III of Fig. II.

Referring more in detail to the drawings, the structural means illustrated comprise a suitable standard 1 having a foot-piece 2 for rigid attachment to the stationary bed 3; of a machine for making, filling and sealing paper, fiber or analogous containers, for example, such as forms the subject-matter of the present inventor's co-pending application for a patent, Serial No. 168,345, filed October 11, 1937. In the prior application referred to, the stationary bed is designated (4) while (5) indicates a vertically movable section thereof or main table, herein characterized 4, whereas 5 are guide means between which the successive container body shells 6 are progressed, said parts, however, forming no features of the present invention.

Surmounting the standard 1 is an appropriate table 7 for the support of an electric motor 8, for operating the flaring head, comprehensively designated 9 and hereinafter described in detail. Adjustable along the standard 1 is a bracket or diametrically-related member 10, one arm 11 of which is fitted with a transverse shaft 12 hav-

ing at its outer ends suitable freely rotative pulleys 13, 13' about which are trained an endless belt or the like 14, in turn driven by a corresponding pulley 15 fixed on one end of the motor shaft 16. The remote portion of the endless belt or the like 14 passes around a coned or stepped pulley 17 on a suitable shaft comprising rotary and non-rotary parts 18, 18', respectively, both mounted in the forked section 19 of the member 10. It is to be noted the pulley 17 is conveniently located in the fork 20 and enables variable speed driving of the shaft 18, and that said shaft 18 serves for rotating the flaring head 9, while the part 18' accommodates raising and lowering of said head, as hereinafter explained. The means 15 for effecting raising and lowering of the flaring head 9 by aid of its supporting drive shaft 18, comprises a lever 22, pivoted at 23 to the upper part 18' of said shaft, and fulcrumed at 24 to a link 25, in turn pivoted at 26 to the forked section 19 of the member 10. To one end of the lever 22 is pivotally attached, at 27, a link or rod 28 having its free end connected to a retractile spring 29 anchored at 30, within a socket or bore 31 provided for the purpose in the member 10. Adjustably coupled by a clamp-device 32 to the lever 22 is a suitable cable 33, passing over an idler 34 attached to the stationary bed 3 and under an appropriate fixed sheave 35, with its free end secured at 36 to the vertically movable table 4.

The flaring head 9, as is known, comprises a body portion 37, for appropriate rigid attachment to the shaft 18, with a circumferential tapering groove 38 intermediate spaced flanges 39, 39', said groove affording a raceway for spaced tapering rollers 40, maintained in cooperative engagement therewith by a floating ring 41 having circumferentially spaced retainer-openings for said rollers.

Assuming, now, for example only, that the container body shell 6 has a thermoplastic lining 42, and that it is appropriately moved into axial alignment below the flaring head 9, it will be readily understood that as the movable table 4 rises, a pull will be exerted on the cable 33 which in turn rocks the lever 22 on its fulcrum 24, and simultaneously lowers the drive shaft 18, by aid of the non-rotary portion 18', and flaring head 9 into the body-shell confronting end. As the flaring-head body portion is rotated by the motor 8, through the means hereinbefore described, it follows that the rollers 40 and cage 41 will be stationarily retained relative to the shaft 18 until said rollers 40 impinge the inner circumfer-

ential edge of the body shell 6, whereupon their direction of rotation will be reversed while the cage 41 follows that of the shaft 18 due to the expansive reaction against said edge of the rollers 40 with incidental production of the slight flare 43, best shown in Fig. II, without in any way damaging the lining 42 or the shell body material, or the conventional spiral seam 44 therein. In practice it has been observed that during the formation of the flare 43 the body-shell 6 remains stationary and requires no holding means to prevent its rotation, also that immediately the flaring head 9 commences its return or upward stroke the flared body-shell 6 remains on the stationary bed 3 or automatically releases itself from any frictional hold by the rollers 40.

From the foregoing the obvious advantages of this invention will be clearly apparent, and while there has been described one preferred embodiment thereof, it is to be expressly understood the same is not to be considered restrictive, as minor changes and other applications of the invention will naturally suggest themselves in adapting the same to differing usage. Accordingly, the right is hereby reserved to all such possible modifications as may reasonably come within the scope of the following claims and the state of the prior art permits.

Having thus described my invention, I claim:

1. In mechanism for cold-flaring thermoplastic-lined paper, fiber or analogous material container body shells preparatory to applying and sealing end closures therein, the combination of a rigid standard sustaining a two-part shaft including a rotary and an axially slidably components, a flaring device comprising concentric converging elements one of which is fixed to the outer end of the rotary component of said shaft and the other is in the form of a floating ring with circumferentially spaced openings for retainer-reception of tapering rollers, means for

driving the shaft rotary component at different speeds, means coactive with the shaft slidable component for moving an axially alignable container body shell into concentric relation with said device, and said floating ring and tapering rollers operating to restrain the body shell against rotation during formation of a slight outward flare around the confronting open end of the container body shell.

2. Mechanism in accordance with claim 1 for cold-flaring container body shell ends of the kind therein specified wherein the rigid standard is vertically disposed and is surmounted by a table affording support for a suitable motor, the two-part shaft is also vertical and its rotary portion has fixed thereon a multiple speed pulley, and said pulley is operatively coordinated by an endless drive and freely rotative idlers with a pulley on the motor shaft for constant rotation at predetermined speed.

3. Mechanism in accordance with claim 1 for cold-flaring container body shells of the kind therein specified wherein the flaring device comprises a body portion having a circumferential tapering groove defined by upper and lower spaced flanges, and a concentric cage member having circumferentially-spaced opening for retaining convergently-disposed freely-rotative individual rollers in operative coaction with the tapering groove aforesaid.

4. Mechanism in accordance with claim 1 for cold-flaring container body-shells of the kind therein specified wherein the means for moving the flaring head comprise a lever pivotally-connected with the shaft axially slidable outer end and also fulcrumed by a link to the rigid standard, one end of said lever being under the influence of retractile means, and the other end of such lever being operatively coordinated to an independently activated reciprocatory means.

JOHN K. M. HARRISON.
